D. M. DUNCAN

COMBUSTION CHAMBER OF BOILER FURNACES

Filed May 8, 1922

Inventor,
David M. Duncan

UNITED STATES PATENT OFFICE.

DAVID MILNE DUNCAN, OF TORONTO, ONTARIO, CANADA.

COMBUSTION CHAMBER OF BOILER FURNACES.

Application filed May 8, 1922. Serial No. 559,456.

To all whom it may concern:

Be it known that I, DAVID MILNE DUNCAN, a subject of the King of Great Britain, and resident of 152 Bartlett Avenue, in the city 5 of Toronto, in the Province of Ontario, in the Dominion of Canada, have invented certain new and useful Improvements in Combustion Chambers of Boiler Furnaces, of which the following is a specification.

10 The invention relates to improvements in the combustion chamber of boiler furnaces as described in the present specification and shown in the accompanying drawing that forms a part of the same.

15 The invention appertains more particularly to combustion chambers for horizontal boilers having an external heating surface, such invention being characterized by a series of transverse grilles disposed to the 20 rear of the grate in the path of the gases and a screen of spaced brick-work; this construction radiating and absorbing the heat thereby preserving an igniting temperature sufficient to effect combustion of unburnt and 25 partially consumed gases; and, furthermore, to precipitate such gases, thus retarding their progress until complete combustion is effected.

The object of the invention is to provide 30 greater efficiency and economy in combustion of fuel in a boiler furnace by auxiliarating incomplete and imperfect combustion of the gases, the enhanced combustion obviating loss of heat and deficiency prevailing in a 35 furnace due to the escape of unconsumed gaseous combustibles.

Referring to the drawing, Figure 1 is a longitudinal sectional view of the boiler.

Figure 2 is a transverse sectional view 40 of the grilles taken on the line 5—5 of Figure 1.

Figure 3 is a further transverse sectional view taken on the line 6—6 of Figure 1 illustrating the screen or baffle wall.

45 Figure 4 is a cross-sectional view taken on the line 7—7 of Figure 2, illustrating the arrangement of the grille.

Figure 5 is a fragmentary view of the screen showing the bricks disposed with an 50 intervening space.

Like numerals of reference indicate corresponding parts in each figure.

In the drawing, 1 designates the boiler proper of conventional construction having 55 the usual furnace grate 2 disposed subjacent the front end thereof and provided with the

necessary fittings, said grate being partially borne by the bridge 3 which keeps the hot gases in close contact with the heating surface of the boiler. The gases as they are 60 generated pass to the rear of the combustion chamber and are deflected by the wall 4 and returned through the tubes of the boiler to the flue or chimney for subsequent discharge. The aforesaid being of customary construction 65 and well known to the art.

5 are the grilles of which there are a plurality, such being arranged transversely and successively from a point slightly to the rear of the bridge 3 and supported a suitable distance from the furnace bottom by angle irons 6 which may either have their ends embedded in the opposing walls or be sustained by stools as at 7, thus providing a substantial area for the passage of the gases below 70 said grilles. The top of the grilles terminate a short distance from the heating surface of the boiler as at 8.

Each grille comprises alternate courses of 80 spaced bricks longitudinally disposed as at 9 and a double spaced row of abutting bricks as at 10 transversely arranged, thus forming a vertical space having communication with the top and bottom of the combustion chamber and also with the intermediate portion thereof through the side openings.

The grilles are constructed of a heat absorbing material, preferably of vitrified brick, and are not bonded or otherwise cemented by mortar.

11 is the screen or baffle wall disposed about the rear extremity of the boiler proper interposing the grilles and the rear wall 4, said screen or baffle wall being supported by cross members 12 similar to the 95 grilles but on a slightly lower plane thereto.

The screen or baffle wall is also constructed of a heat absorbing material such as the aforesaid vitrified brick and is likewise unbonded; each brick being isolated from the adjacent one by a space or void, such space being comparatively small and may be obtained by making projections on the bricks or otherwise secured as may be found convenient.

105 In the operation of this invention, the gases as they are generated by the burning fuel are carried by the draft rearwardly over the bridge 3, the lighter and hotter gases rising over the grilles contacting with the heating surface of the boiler proper. The less buoyant gaseous particles which

comprise the unignited elements and constituents deficient in oxygen are retarded by their impingement upon the grilles deflecting and precipitating same downwardly 5 through and about the various openings in said grilles. The heat thus emitted effecting the ignition of such gases and permits of their union with oxygen in order to complete combustion thereof. The screen 10 co-acting with the grilles to effect complete combustion deflects the major portion of the gases downwardly, the residue passing through the spaces or voids therein, thus causing some of the slow burning particles 15 to be completely consumed by their retention between the heated bricks and others by their deflection.

What I claim is:—

1. The combination in a combustion 20 chamber of a boiler furnace, of a transverse screen removed from the furnace bottom constructed of isolated brick-work forming

small spaces for the passage of hot gases, and spaced grilles interposing the said screen and a gate bridge, said grilles being 25 removed from the furnace bottom, each grille comprising alternate courses of spaced longitudinal bricks and a double row of spaced transverse bricks.

2. In a combustion chamber of a boiler 30 furnace, a series of transverse grilles removed from the furnace bottom, each individual grille comprising alternate courses of spaced bricks longitudinally disposed and a double row of transverse bricks having abutting ends, and a space interposing 35 said double row of bricks; said individual grilles each being independently supported by angle irons disposed subjacent each of the transverse row of bricks, said angle irons not being of a greater width than the same in order not to prevent precipitation 40 of carbon.

DAVID MILNE DUNCAN.
